Application October 12, 1946, Serial No. 703,013
In Great Britain November 3, 1945

19 Claims. (Cl. 315—6)

1

The present invention relates to electron beam valves and, more particularly speaking to valves furnished with an electrical cavity resonator.

In such valves, some of the energy in an electron beam is transferred to oscillatory fields in the cavity resonator. These fields constitute standing electromagnetic waves within the cavity. The proportion of the total input electron beam energy which is transformed into wave energy in this way is usually referred to as the "efficiency" of the valve.

To effect this transfer of energy, it is necessary to establish along the path of the beam of electrons an electric field of certain shape, directions, and magnitudes.

As far as is known, the shapes, directions and magnitudes of the field, actually found inside any one of known kinds of resonant cavity depart very substantially from those necessary to convert a really substantial portion of the D.-C. energy of the beam into oscillatory output energy. Therefore, although electron beam valves have been proposed in which a beam of electrons has been set up and a cavity resonator employed, such known forms of valve have cavities of such a shape that the fields therein are such that the efficiency of conversion of input electron beam energy to oscillatory power is very low. Therefore, these valves have only a very limited usefulness. For example, a reflection type of velocity modulation valve furnished with a single resonant cavity, has an efficiency, in practice, of only the order of about 5% or less and that of a diode furnished with a single resonant cavity is even less.

Moreover, when used at extremely short wavelengths, the cavity resonators hitherto employed are usually so small as seriously to limit the power output which the valve can handle.

One of the objects, therefore, of the present invention is to produce an electron beam valve provided with a single cavity resonator in which cavity there is an internal field of shape, magnitude, and direction such that a comparatively high efficiency is produced, and a further object of the invention is to provide resonant cavities for use in such valves, which are large at a given wavelength compared with those hitherto available.

In order to make the present invention, it has been found necessary to carry out investigations to increase the knowledge available of both electrons beams and resonant cavities. These two investigations were as follows:

(a) The shape, magnitude, and direction of the

2

oscillatory fields which are best placed in the path of a beam of electrons in order to convert the D.-C. power of the beam into oscillatory output power in an efficient manner have been investigated, both mathematically and experimentally. This investigation has yielded certain information which is believed to be new, or at least, not fully appreciated or explained previously.

(b) Another investigation into the field shapes, magnitudes, and directions, which can in fact be obtained in resonant cavities for use in electron beam valves has also been carried out. In general, prior knowledge has not been such that it was possible to predetermine or calculate these field shapes. This is because it is not practicable, in the more complex and useful cases, to solve certain basic differential equations. An experimental approach was also difficult, as it is necessary to study the magnitude and direction of the field at all points within a large number of shapes of resonant cavity. As far as is known, no suitable measuring device, or method of doing this, has hitherto been known.

By means of a new method of measurement and new measuring devices partly described below, it has been possible to devise a new shape of cavity resonator having fields of new shapes, magnitudes, and directions. This new shape of cavity has certain unique features, and is especially useful in electron beam valves, and inter alia forms part of the present invention.

By building, therefore, upon the results of both these investigations, the present invention has been made and according to the invention an electron beam valve is furnished with a resonator in which there are an input sub-cavity, a main sub-cavity and an output sub-cavity, abutting in that order one upon the other, the input and main sub-cavities being separated by an input septum, and the main and output sub-cavities being separated by an output septum; the outside wall of the input sub-cavity is formed with a beam entrance aperture across an axis which is common to the three sub-cavities while the input septum is substantially complete except for a substantially parallel-sided deflection slot lying across the said axis; the output septum is also substantially complete except for the provision of a substantially parallel-sided slot lying across the said axis, and a grid is placed alongside that slot; the deflection slot and the slot in the output septum are parallel; the cathode and beam forming means are arranged so that the electron beam when produced will pass through the beam

entrance aperture, along the axis into the input sub-cavity and onto the deflector slot so that for at least one mode of resonance of the resonator an alternating electric field transverse to the axis exists across the deflection slot and an output electric field substantially parallel to the axis exists in the output sub-cavity between the said grid and the opposite wall of the output cavity and the field in the greater part of the main sub-cavity is of less magnitude than either of these latter fields.

A pair of grids may be provided on either side of the slot in the output septum. The axis need not be in the centre of the sub-cavities.

The grid may be provided with one aperture or many of circular, rectangular, or other shapes.

Again, a part of the outside wall of the output cavity is conveniently arranged to project towards the output septum opposite the area of that septum where the grid or grids are placed.

The relative dimensions of the input and output sub-cavities may be such that at at least one mode of resonance of the resonant cavity, an electric field transverse to the axis exists across the deflection slot and output electric fields substantially parallel to the axis exist in the output sub-cavity opposite the grid or grids, the ratio between the magnitude of the transverse electric field and the magnitude of the output electric field being such that at some working potential upon the resonant cavity, with respect to the cathode, and when the said electron beam enters the cavity, continuous oscillations are generated.

In order that the invention may be clearly understood and readily carried into effect, some examples or particular forms of construction of the invention will now be more fully described with reference to the accompanying drawings, in which:

Figure 1 is an explanatory diagram of electric fields;

Figure 2 is an axial section of a complete valve in accordance with the invention;

Figure 3 is a perspective view of the left-hand half of the cavity resonator shown in Fig. 2;

Figure 4 is an exploded view of the pressings used to make up the cavity resonator shown in Fig. 2;

Figure 5 is a curve or graph used in the design of the structure;

Figure 6 is a diagrammatic axial section of a wooden model of half the cavity resonator covered with copper sheet and used in testing the design;

Figures 7 and 8 show two more explanatory curves or graphs;

Figure 9 is a perspective view of an alternative form of cavity resonator of square shape;

Figure 10 is a section of a somewhat modified form of cavity resonator;

Figure 11 is a section of another modification with the back grids altogether omitted;

Figure 12 is a side elevation; and

Figure 13 is a plan of a number of cavity resonators with a wave guide leading off from one side; while

Figure 14 is a diagram of a cavity resonator to illustrate modes of application of the invention.

In Figure 1 an electron beam 1 is shown travelling through a system of electric fields having the co-ordinates ox and oy so as to deliver oscillatory energy to these fields. For this pur-

pose, the beam enters the field system at a velocity v_{ox} in the ox direction, and passes first through an oy -directed or transverse input oscillatory field 2. This field 2 causes the beam to be deflected transversely in an oscillatory manner between the two positions 3 and 4 shown by the dotted lines. The beam travels across a field-free space 5 and is deflected alternately into two output fields 6, 7, which are in opposite phase or pushpull and are oscillatory at the same frequency as the input field 2. In the course of the investigation (a) mentioned above, it was found that the energy required to deflect the electron beam as shown in Fig. 1 is very small compared with the power carried by the electron beam. If the electron beam enters the oscillatory output electric fields 6, 7 at an appropriate phase compared with the input field 2, and if the magnitude of these fields is appropriate then a substantial portion of the electron beam energy will be transferred to the output fields 6, 7. The difference in phase between the input field 2 and the output fields 6, 7 will be determined by the transit time of the electrons between the input field 2 and the output fields 6, 7, across the field-free space 5 between them. If, moreover, all the fields 1, 6 and 7 are part of the same field system, some of the energy delivered to the output fields 6, 7, by the electron beam 1 will appear in the input field 2, and if the above-mentioned phase is suitable and sufficient energy is delivered by the beam 1, a regenerative effect will take place, and the system as a whole can generate continuous oscillations.

Such a field system is used in electron beam valves in accordance with the present invention.

In Fig. 2 the cross-section of a cavity resonator 8 made in accordance with the present invention is shown diagrammatically as well as an electron beam 1 which is represented diagrammatically as having been produced by an electron gun of known type comprising a straight cathode 9 and shield 10 at or near cathode potential. The electron beam then travels through a slot 10a in a beam forming pressing 26, into the resonator through an entrance slot 11. The shape of the resonator 8 is, in accordance with the present invention, such that the electron beam 1 therein passes through and co-operates with an oscillatory field system such as that explained with reference to Fig. 1.

The beam 1 then passes through a deflecting or input slot 12 and then travels across the space 5 in which there is only a relatively small field and then through an outlet slot 12a. When the beam is deflected, it passes alternately through two pairs of grids g_1, g_2 and g_3, g_4 , and finally strikes a back plate 13.

In order to accelerate the beam through the entrance slot 11 in this manner, the resonator 8 is maintained by a battery, or the like (not shown), at a positive potential V_b with respect to the cathode, applied to a terminal 14.

Such a resonant cavity 8 possesses a mode of resonance at which there exists an intense oscillatory electric field across the slot 12, which field is transverse to the initial entrance direction of the electron beam 1. The electric field in the space 5 is much weaker than that in the slot 12, but is also substantially transverse to the entrance direction of the electron beam. There also exist two output fields in the gaps 15, 16, respectively between the pair of grids g_1, g_2 and the pair of grids g_3, g_4 , so that the electron beam 1 is alternately deflected through them by the trans-

verse field at the slot 12. These two output fields at the gaps 15, 16 have directions substantially parallel to the entrance direction of the electron beam at the entrance slot 11, and are 180 degrees out of phase with each other, that is to say, they are in pushpull. The electron beam 1 after passing through the pairs of grids g1, g2, and g3, g4, impinges upon the back plate 13; the space 17 between this back plate 13 and the nearest grids g2 and g4, being substantially free of field.

The system shown in Fig. 2 will be recognized as providing oscillatory electric fields within the cavity resonator 8 which are closely equivalent, and in fact operate similarly, with respect to the electron beam 1, as the fields 2, 6 and 7 in Fig. 1 operate with the electron beam 1 in that figure.

As explained with reference to Fig. 1, the electric fields in the cavity resonator 8 in Fig. 2 are part of the same system, and energy delivered from the electron beam 1 to the output fields in the spaces 15, 16 will appear in the input deflection field in the slot 12. If the phase relation between the deflections at the slot 12 and at the output fields at 15 and 16 is appropriate, and the losses of the system are not too great, then the beam 1 will be set into continuous transverse oscillation, and the system will generate oscillatory energy.

This energy may be fed out from the left-hand end of the cavity resonator 8, by known means. For example, through slots cut in the wall of the output sub-cavity 21 of the resonator, into a wave guide shown diagrammatically at 18 in Figure 2, and by way of this wave guide 18 energy may be fed into a load (not shown). The overall transit angle which determines the phase relation abovementioned will be principally proportional to the distance x2 in Fig. 2, and inversely proportional to the square root of the potential Vb at which the resonator is maintained with respect to the cathode 9 and to the mode and wavelength at which the resonator 8 is operated.

It will also be necessary for the magnitude of the transverse input field in the slot 12 to bear an appropriate ratio to the magnitude of the output fields in the spaces 15, 16. Therefore if E_y is the maximum instantaneous value of the maximum transverse input field in the slot 12 and E_x is the maximum instantaneous value of a maximum field in the path of the electron beam 1 in the spaces 15, 16, an important parameter will be the ratio K = E_y/E_x.

It will be observed that the resonant cavity 8 in Fig. 2 consists of three sub-cavities which will be referred to respectively as the input sub-cavity 19, the main sub-cavity 20, and the output sub-cavity 21. The sub-cavities 19 and 20 are separated by an input septum 22 and sub-cavities 20 and 21 by an output septum 23. It is an important feature of the invention that in resonators constructed according to the invention, the ratio K is adjustable in a smooth and continuous manner by adjusting the relative dimensions of the sub-cavities 19 and 20. K will be recognised as somewhat equivalent to a control of regeneration, and may be adjusted if required so that continuous oscillations are produced. In this manner, a proper control of the oscillations and load characteristics of the electron beam valve in accordance with the invention is obtained.

It will be realised that electrons in the beam 1, in passing through the grids g1, g2, and g3, g4 in Fig. 2 will produce secondary electrons, and that

unless the well known deleterious effect of these secondary electrons is eliminated, their presence may cause a serious loss of efficiency.

In the copending patent application Serial No. 637,194, filed December 26, 1945, a method of preventing the deleterious effect of secondary electrons is described, consisting briefly of setting the distance d in Fig. 2 (with respect to the potential V_b and the wavelength λ in centimeters corresponding to the mode of oscillation used) so that secondary electron emission is "suppressed" and rendered harmless. This "suppression" will take place if the transit angle ϕ satisfies the following equation:

$$\phi = 3.3 \times 10^{-8} \frac{fd\pi}{\sqrt{V_b}} \quad \text{Equation A}$$

In this equation f is the frequency corresponding to the wavelength λ . Thus, as set forth in said copending application, the transit angle ϕ may be from 0.25π radians to 0.8π radians. To assist this suppression of secondary electrons, the grids g1, g2, g3, g4, and the backing plate 13, may also be roughened and coated with colloidal graphite.

The present invention may therefore be combined in this way with the invention set forth in the said co-pending patent application.

Alternatively it may be found convenient in some cases to use other known methods of suppressing secondary electrons.

In the arrangement shown in Fig. 2, the backing plate 13 may be removed, and the electrons in the beam 1 after passing through the pairs of grids g1, g2, g3, g4, may be collected in a bucket or like electrode (not shown) which should be of low enough potential to waste as little energy as possible.

The cavity resonator in accordance with the invention may conveniently be manufactured of copper pressings shown separated in Fig. 4 and which are welded together by mounting them on a jig in a vacuum with silver foil interleaved between them and heating them by means of an eddy current furnace, until the silver foil placed between the pressings is melted and welds the pressings together. As shown in Figure 4, the main sub-cavity 8 is formed of two cup-like elements joined together in axial alignment with their open ends in abutting relation, and the input and output sub-cavities 19 and 21 are formed respectively of cup-like elements of smaller size arranged in axial alignment with cups 29 and 30 and having their open ends joined respectively to the outside faces of the bottom walls of cups 29 and 30. The various slots, apertures and grids may be cut from a master template by a pantograph type of engraving machine. Where necessary the copper pressings may be held by wax to a brass backing plate during this process.

Fig. 2 shows a section of a resonator constructed in this way. It is shown in greater detail in Figs. 3 and 4.

Figure 3 shows diagrammatically the beam 1 when undeflected, and a half-section in perspective of the cavity resonator 8 illustrated in Fig. 2, together with the nomenclature of certain important dimensions of the resonator.

The beam entrance slot 11 is 1.7 mm. x 5.5 mm. long. Its length must not be so great that appreciable radio frequency energy is radiated through it when the resonator is in operation. The electron beam 1 is preferably arranged (by suitable known design of the electron gun 9, 10, Fig. 2 (not shown in Fig. 3)) to have its narrowest dimension (preferably the crossover point of the

electrons) in the neighbourhood of the input slot 12, and should have dimensions at the plane of the grids g_1 and g_2 Fig. 2, such that as much as possible of the beam will pass through the appropriate grid g_1 or g_2 when it is deflected.

The following is a list of the above-mentioned important dimensions of the resonator 8, with specific reference to the symbols shown in Figs. 3 and 4.

- $x_1 = 2.53$ millimeters.
- $x_2 = 17.5$ millimeters.
- $x_3 = 3.8$ mms.
- $r_1 = 12.125$ mms. approximately.
- $r_2 = 15$ millimeters.
- $r_3 = 11$ millimeters.
- $d_1 = 1.7$ mms.
- $d_2 = 1.25$ mms.
- $d = 1.3$ millimeters.
- $l_1 = 1$ millimeter.
- $l_2 = 1$ millimeter.
- $b = 12$ mms. approximately
- $a = 6$ mms.

The adjustments of the dimensions r_1 , a , and b will be referred to later.

The flat surface 24 through which the grids g_2 and g_4 are cut is 10 x 10 millimeters. The sides of the sub-cavity 21 slope away from its flat surface as shown. The grids g_1 , g_2 , g_3 and g_4 , are all of exactly the same dimensions, and consist each of 5 slots with rounded ends, each slot being 4 mm. long and 1.2 mm. wide, the width of the bars between the slots being approximately 0.25 mm.

These dimensions should preferably be maintained within a tolerance of ± 0.025 millimeter.

Figure 4 shows an exploded view of a set of those pressings used to form the resonator 8 in accordance with the present invention, a perspective section of which is shown in Fig. 3. Holes 25 of 1 1/2 millimeter diameter, spaced 15 mm. apart, are cut in all the pressings so that they may be mounted on a jig which consists of two rods in a holder (not shown) and then clamped with silver foil between them for the purpose of welding them together as previously explained. The pressings are preferably made of oxygen-free high-conductivity copper sheet. The centre hole 25a in the backing plate 13 is finally closed by a screw 13a. The pressing 26 provides a curved surface 27 on the face of the resonant cavity next to the gun 9, 10 in Fig. 2, which curved surface has contours arranged in known manner to assist in forming the electron beam. A pair of output coupling slots mentioned in connection with Fig. 2, above is shown at 28 in Fig. 4.

It will be observed from Figs. 2, 3, and 4, that the thickness of the pressings 29 and 30 is arranged to be 1 mm., so that the specified thicknesses and widths l_1 and l_2 indicated on Fig. 3 are obtained.

It will be appreciated that the dimensions a and b , and the exact shape in particular of the output sub-cavity 21, and the rest of the sub-cavities, will depend in any given case upon the exact configuration of the pressings which are produced by the press tool. During construction, it has been found convenient to adjust the radius r_1 to compensate for this and so to provide the desired values of the ratio K previously mentioned. The desired field configurations will, in general, be found at those two modes of oscillation of the resonator to be referred to respectively as the first or longest wavelength mode, and a second mode which differs slightly from

the first in wavelength. Preferably the first or longest wavelength mode is employed, and the resonant wavelength of the resonator the dimensions of which are quoted above is about 4.1 centimeters.

As seen in Fig. 2, the resonator 8 is fixed by screws 31 to a flat ring 32 provided with fins 33 on its opposite faces to which the two halves 34, 35 of the glass envelope are sealed. For mounting the valve, the ring 32 is clamped by means of screws 36 between the flange 37 of the wave-guide 18 and a clamping ring 38. The terminal 14 is screwed on to one of the screws 36. The gun 9, 10 is mounted on a transverse insulating bar 39 of ceramic material clamped to a similar bar 40 at right angles to it and which, in turn is carried by two copper tubes 41 welded on to the outside of the resonator 8. The cathode lead in wires are shown at 42.

Fig. 5 shows a typical curve or graph of the relationship between the diameter $2r_1$ of the input cavity 19 and the ratio K . Similar graphs may be drawn, and adjustments made, with regard to r_2 , x_1 , and x_2 .

In general, resonant cavities in accordance with the present invention will be used at wavelengths so short that the physical size of these cavities is too small for electrical test measurements to be conveniently made on them, for the purpose, for example, of adjusting r_1 to allow for the effect of accidental or deliberate alterations in the contours of the various sub-cavities so that K is maintained at a chosen value.

Therefore for the purpose of such adjustments and general checks a technique has been developed for making an exact scale model of the working resonator in question. These scale modes may be, for example, 25.4 times the linear dimensions of the working cavity, so that each inch of the model represents 1 millimeter of the working resonator. The model is preferably one representing a half of the resonator only, as shown in Fig. 6, the division being along a plane of symmetry parallel to the slot 12. In the model this plane of symmetry may consist of a thin copper sheet. A convenient construction for the model consists of a wooden frame 43 covered by copper sheet 44 which is carefully soldered at all the joints.

In order to adjust such dimensions as r_1 to obtain a desired value of K , the model resonator is excited by the injection from a signal generator of a small amount of radio frequency energy of the appropriate (scaled-up) wavelength. By means of a small probe projecting into the model at the appropriate places, the ratio $E_y/E_x = k$ may be measured. A probe may be inserted, for example, in the slot 12 through the copper sheet covering the plane of symmetry in the model so as to measure E_y , and E_x may be measured by the same probe inserted in a similar manner, and with the same degree of projection, through one of the grid bars in g_2 or g_4 . The field between the spaces of the grids g_1 , g_2 , g_3 , g_4 , may be taken as about 0.8 of the value measured in this way between two opposite slots. It will be appreciated that, by transferring the contours of the actual pressings shown in Fig. 4 on to the model resonator shown in Fig. 6 the model and the actual resonator may be made identical in shape and by adjustments of, for example, r_1 , K may be adjusted.

A useful value of K will be of the order of 0.8. In the course of the investigation (a) referred to above, it has been found that during operation

the field integral of E_x across the distance d in the spaces 15, 16 between the two pairs of grids $g1, g2$ and $g3, g4$ should be about equal to the positive voltage V_b applied to the resonator with respect to the cathode. Therefore

$$V_b = E_x d \text{ and } K = \frac{E_y}{E_x}$$

and

$$K = \frac{E_y d}{V_b} \quad (1)$$

where d is the distance so marked in Figs. 2 and 3.

The amount y_x by which the electron beam is deflected from the plane of symmetry of the resonator towards either of the pairs of grids $g1, g2$ or $g3, g4$ will be proportional to the shape of the transverse electric field along the plane of symmetry of the resonator, upon which plane the entrance direction of the beam of electrons lies. This plot of transverse electric field may be made on the model resonator as shown in Fig. 6, and if desired the deflection of x may be approximately calculated by known methods of graphical integration of this field having regard to the wavelength of operation and the potential V_b .

Fig. 6 shows a section of the resonator model. The copper plate previously mentioned covers the plane of symmetry 45. The transverse electric field E on this plane is plotted (as shown) in terms of E_x , that is, the ordinates of the curve in Figure 6 are in terms of the ratio E/E_x . The boundary of a typical undeflected electron beam is shown by the dotted line 1 and its narrowest point by 46. The scale along the plane of symmetry 45 is divided into inches in the model, which is the equivalent to millimeters in the actual working resonator.

In further explanation, Fig. 7 shows a typical graph of transverse field E along the distance x_1+x_2 on the plane of symmetry such as that shown in Fig. 6, the field being plotted in terms of E_y , that is, the ordinates of the curve of Figure 7 are in terms of the ratio E/E_y .

Fig. 8 shows a plot of the approximate deflection in centimetres at the grids of the resonator as a function of V_b for $K=1$.

Instead of the sub-cavities being of cylindrical configuration as in Figs. 2, 3, 4 and 6, they may be of rectangular or other shape. A rectangular shape is illustrated diagrammatically in Fig. 9 as a half of the resonator divided along the plane of symmetry. Corresponding reference numerals to those employed in Fig. 3 are used and the construction can be easily followed by comparison with that figure.

Whilst the preferred shape of resonators is that already illustrated, the re-entrant portion 47 in Figs. 3 and 9 may be omitted. The distance x_3 may then equal d , and the grids $g2$ and $g4$ (Fig. 2) left as before. Such a modified shape is shown diagrammatically in section in Fig. 10. The axis of the undeflected beam is indicated by the dotted line 48.

According to a further modification, after passing through the grids $g2$ and $g4$ in the output septum 48 in Figs. 2, 3, 8 etc. the electrons may be caught by a backing plate (not shown) or by a low potential bucket.

Fig. 11 shows a further modification according to which the grids $g2$ and $g4$ are omitted altogether. This modification may also be applied to the resonators of the kind illustrated in Figs. 2, 75

3, 4, 6 and 9. In general, however, the power output efficiency will be less when using this modification than when all four grids $g1, g2, g3, g4$ are used.

5 Resonant cavities in accordance with the invention, and particularly those of square configuration such as Fig. 9, may be mounted together and coupled tightly to each other by intercoupling slots in walls common to both cavities so as to operate additively as regards power output and in conjunction with a common cathode assembly. In Fig. 12, the resonant cavities 8a, 8b, 8c, are coupled by slots (not shown) in this manner and are arranged by means of a further slot (not shown) to feed their radio frequency energy into a wave guide 49. The cathode 9a is provided with a zero potential shield 10a in which slots 50 are provided, so that three beams of electrons (not shown) pass through these slots into the resonators 8a, 8b and 8c, in accordance with the invention. The shield 10a is shaped in known manner in the neighbourhood of the slots 50, and the resonators 8a, 8b and 8c, are correspondingly shaped in Fig. 11 at 51 opposite the slots 50 so that the beams of electron are shaped in accordance with the present invention.

15 The three cavity resonators 8a, 8b, 8c, can therefore be set into oscillation simultaneously and radio frequency power will be delivered by all 20 three together into the wave guide 49, down which the power may be led to a load (not shown).

25 Fig. 14 shows a cavity resonator 8 as in Fig. 2, with an electron gun 9b, 10b, and a beam of electrons 1 which is shown undeflected. A probe electrode 52 is arranged so that the electrons in the beam 1 induce a current in the probe 52 which is proportional to the position of the beam 1. The current to this probe is led to a controlling means 53, which is operated thereby in accordance with 30 the amplitude of the oscillations of the electron beam 1. Potentials from the controlling means 53 may be fed back by means of the line 54 shown in dotted lines to the electron gun 9b, 10b, so as to 35 modify the potential of one or more of the electrodes therein. As will be appreciated, the amplitude of the oscillations produced by the beam 1 in the resonator 8 may be controlled in proportion to the potentials applied to one or more of the electrodes of such an electron gun 9b, 10b.

40 45 50 By this means, the power output of the device may be stabilised and controlled.

Alternatively, the output from the control means 53 may be led by a line 55 to recording means not shown.

55 It will be appreciated that the electron beam in an electron beam valve in accordance with the present invention may be modulated by applying potentials to the electrodes of the electron gun, or to the cavity resonator, in many useful ways, and such valves may be employed both for transmission and reception.

60 65 Alternatively to the forms of construction previously mentioned, built up of metal pressings, the resonator may be machined from solid metal or built up out of flat stampings.

70 It will be realised that the present invention may be employed not only for the generation of oscillations but for the detection of oscillations and for the reception, as well as for the transmission, of electromagnetic waves.

The control of regeneration by the magnitude of K may be used for many known purposes. The output from the probe 52 in Fig. 14 may be employed for detection purposes, the degree

11

of regeneration being then preferably such as not to set the valve into oscillation.

The resonator shape shown may be modified in detail, but if d_1 , d_2 or d are made too small difficulties may be found in obtaining the desired field shapes in a suitable manner. Any apertures in the septa 22, 23 (Figs. 2, 3, and 9), should not be so large as to destroy the shielding of these walls.

I claim:

1. In an electron discharge device, the combination of a hollow resonator having an input sub-cavity and a main sub-cavity separated by an input septum, and an output sub-cavity separated from the main sub-cavity by an output septum, the input and output sub-cavities being substantially smaller in transverse area and in axial dimension than the main sub-cavity, the outside wall of the input sub-cavity having an electron beam entrance aperture formed therein, an electron gun positioned to direct an electron beam through said aperture along an axis directed through said input and output septa, the input septum having an elongated deflection slot formed therein across said axis, the output septum having an elongated slot formed therein across said axis and parallel to said deflection slot, and a portion of said output septum adjacent the slot therein being apertured thereby forming a grid element.

2. An electron discharge device according to claim 1 in which the deflection slot and the slot in the output septum extend entirely across the input and output sub-cavities respectively.

3. An electron discharge device according to claim 2 in which a part of the outside wall of the output sub-cavity opposite the area of the grid portion of the output septum is formed as a re-entrant portion projecting towards the output septum.

4. An electron discharge device according to claim 3 in which portions of the output septum on opposite sides of the slot therein are perforated thereby forming a pair of grid elements.

5. An electron discharge device according to claim 4 in which said re-entrant portion of the outside wall of the output sub-cavity is provided with an elongated slot in alignment with the slots in said septa, and said re-entrant portion being apertured on opposite sides of the slot therein thereby forming a second pair of grid elements in alignment with the pair of grid elements in the output septum.

6. An electron discharge device according to claim 5 in which the electron beam produced by said electron gun has its minimum width near the point at which it passes through the deflection slot in the input septum, and passes through the grid elements in the output septum when deflected by said deflection slot.

7. An electron discharge device according to claim 1 in which a part of the outside wall of the output sub-cavity opposite the area of the grid portion of the output septum is formed as a re-entrant portion projecting towards the output septum.

8. An electron discharge device according to claim 7 in which portions of the output septum on opposite sides of the slot therein are perforated thereby forming a pair of grid elements.

9. An electron discharge device according to claim 8 in which said re-entrant portion of the outside wall of the output sub-cavity is provided with an elongated slot in alignment with the slots in said septa, and said re-entrant portion

10

being apertured on opposite sides of the slot therein thereby forming a second pair of grid elements in alignment with the pair of grid elements in the output septum.

10. An electron discharge device according to claim 1 in which the electron beam produced by said electron gun has its minimum width near the point at which it passes through the deflection slot in the input septum, and passes through the grid elements in the output septum when deflected by said deflection slot.

11. An electron discharge device according to claim 1 wherein for one mode of resonance of the resonator, the distance between the output septum and the inner side of the output wall of the output sub-cavity corresponds to a small signal transit angle not less than about 0.25π radians and not greater than about 0.8π radians at the operating frequency of the device.

12. An electron discharge device according to claim 11 in which the deflection slot and the slot in the output septum extend entirely across the input and output sub-cavities respectively.

13. An electron discharge device according to claim 11 in which a part of the outside wall of the output sub-cavity opposite the area of the grid portion of the output septum is formed as a re-entrant portion projecting towards the output septum.

14. An electron discharge device according to claim 11 in which portions of the output septum on opposite sides of the slot therein are perforated thereby forming a pair of grid elements.

15. An electron beam tube comprising a hollow resonator having an input sub-cavity and a main sub-cavity separated by an input septum, and an output sub-cavity separated from the main sub-cavity by an output septum, the three sub-cavities being aligned on a common axis and the input and output sub-cavities being substantially smaller in transverse area and in axial dimension than the main sub-cavity, the outside wall of the input sub-cavity having an electron beam entrance aperture formed therein across said common axis, the input septum having an elongated deflection slot formed therein across said common axis, the output septum having an elongated slot formed therein across said common axis and parallel to said deflection slot, and a portion of said output septum adjacent the slot therein being apertured thereby forming a grid element.

16. A cavity resonator comprising a pair of metallic cup-like elements joined together in axial alignment with their open ends in abutting relation to form a main sub-cavity, a second pair of cup-like elements of smaller size than said first pair arranged in axial alignment with said first pair of cups and having their open ends joined respectively to the outside faces of the bottom walls of said first pair of cups to form a pair of sub-cavities at opposite ends of said main sub-cavity, the bottom walls of said first pair of cups having elongated slots formed therein in a common plane and extending throughout the widths of said smaller cups, one of said smaller cups comprising an entrance cup having an entrance aperture formed in the bottom wall thereof in said common plane, and the bottom wall of the larger cup joined to the other smaller cup being apertured on opposite sides of the elongated slot formed therein thereby forming a pair of grid elements.

17. A cavity resonator according to claim 16 wherein said smaller cup joined to the larger

75

13

cup having grid elements is provided with a re-entrant portion in the bottom wall thereof and in alignment with said grid elements, said re-entrant portion having an elongated slot formed therein in alignment with the slots in said larger cups, and said re-entrant portion being apertured on opposite sides of said slot thereby forming a second pair of grid elements aligned with said first pair of grid elements.

18. An electron discharge device according to claim 1 and including a pickup probe mounted within said hollow resonator in a position to be influenced by said electron beam.

19. An electron discharge device according to claim 1 in which portions of the output septum on opposite sides of the slot therein are perforated thereby forming a pair of grid elements, a part of the outside wall of the output sub-cavity opposite the area of the grid portions of the output septum being formed as a re-entrant portion projecting towards the output septum, said re-entrant portion of the outside wall of the output sub-cavity being provided with an elongated slot

15

14

in alignment with the slots in said septa, said re-entrant portion being apertured on opposite sides of the slot therein thereby forming a second pair of grid elements in alignment with the pair of grid elements in the output septum, and a pickup probe mounted within the elongated slot formed in the re-entrant portion of the outside wall of the output sub-cavity.

JOHN HENRY OWEN HARRIES.
